US00D632234S

(12) **United States Design Patent**
Peltola et al.

(10) **Patent No.:** **US D632,234 S**
(45) **Date of Patent:** **** Feb. 8, 2011**

(54) **TOP PANEL FOR TRUCK HOOD**

(75) Inventors: **Wallace A Peltola**, Sammamish, WA (US); **Jonathan Duncan**, Seattle, WA (US); **Steven H Hovind**, Bellevue, WA (US); **Alec C Wong**, Bellevue, WA (US); **Steven L Baker**, Duvall, WA (US); **Erik D Hjorten**, Everett, WA (US); **Casey W Keil**, Renton, WA (US); **Jonathan F Wilkens**, Kirkland, WA (US)

(73) Assignee: **PACCAR Inc**, Bellevue, WA (US)

(**) Term: **14 Years**

(21) Appl. No.: **29/360,585**

(22) Filed: **Apr. 28, 2010**

(51) **LOC (9) Cl.** **12-16**

(52) **U.S. Cl.** **D12/173; D12/196**

(58) **Field of Classification Search** D12/96, D12/97, 98, 12, 90-92, 173; 296/180.1-180.3, 296/181.1-185, 186, 186.1; 180/89.12, 89.1, 180/242, 449

See application file for complete search history.

(57) **CLAIM**

The ornamental design for a top panel for truck hood, as shown and described.

DESCRIPTION

FIG. 1 is a right front perspective view of a top panel for truck hood showing our new design;

FIG. 2 is a front elevational view of the top panel for truck hood of FIG. 1;

FIG. 3 is a rear elevational view of the top panel for truck hood of FIG. 1;

FIG. 4 is a top plan view of the top panel for truck hood of FIG. 1;

FIG. 5 is a bottom plan view of the top panel for truck hood of FIG. 1; and,

FIG. 6 is a right side elevational view of the top panel for truck hood of FIG. 1, the left side elevational view being mirror symmetrical to FIG. 6.

1 Claim, 5 Drawing Sheets
